UNITED STATES PATENT OFFICE.

PETER GRAHAM MACGREGOR, OF PEQUANNOCK, NEW JERSEY, ASSIGNOR TO PYRENE MANUFACTURING COMPANY, OF NEWARK, NEW JERSEY, A CORPORATION OF DELAWARE.

RELIEF VALVE FOR FIRE-EXTINGUISHER PUMPS.

Application filed May 5, 1927. Serial No. 188,974.

This invention relates to relief valves for fire-extinguisher pumps of the type adapted to forcibly eject the fire extinguishing liquid from the liquid receptacle through an outlet tube or nozzle on both the inward and outward strokes of the pump piston.

In fire extinguishers in which the above mentioned types of pumps are employed, the outlet tube or nozzle is restricted in cross 10 sectional area in comparison with the effective cross sectional area of the pump, and as a result of the difference between these two cross sectional areas the action of the pump is apparently rendered stiff or restrained 15 when an attempt is made to operate it at a high rate of speed, as is the tendency of one laboring under the strain of excitement usually incident to the unexpected outbreak of fire.

20 An object of this invention is to obviate or lessen the above mentioned apparent stiffness in the operation of the pump, without distracting from the efficiency of the extinguisher, and to this end the invention resides 25 in the provision of a novel relief valve mechanism which is adapted to permit a small quantity of liquid to escape from the pressure side of the pump piston back into the liquid receptacle.

30 Other objects and advantages of the invention will become apparent from the following description when taken in connection with the drawings in which,

Figure 1 is a view in elevation of a pump fitting or head embodying this invention; Figure 2 is a horizontal sectional view taken on the line 2—2 of Figure 1, showing the intake valve closed and the relief valve open, Figure 3 is a view, similar to Figure 2, but 40 showing the intake valve open and the relief valve closed; Figure 4 is a vertical sectional view taken on the line 4—4 of Figure 3; Figure 5 is a vertical sectional view taken on the line 5—5 of Figure 2; Figure 6 is a perspective view of the valve cage and the closure for the valve chamber; and Figure 7 is a perspective view of the valve cage as viewed from above in Figure 6 and somewhat to the right and rear.

50 While only one fitting is herein shown, it will be understood that when the invention is applied to a double acting pump of the type shown in my copending application Serial No. 60,708, filed October 6, 1925, two of

such fittings may be employed, one at one 55 end of the pump cylinder and the other at the other end thereof. The fitting or head 9 herein shown is in the form of a casting which is cored or otherwise provided with a chamber 10 which communicates with and 60 forms one end of a pump cylinder, not shown, adapted to fit the counterbored end 11 of the casting. The head 10 includes a depending skirt 12 adapted for the reception of suitable packing, not shown, through which the usual nozzle tube, also not shown, is adapted to extend, into which nozzle tube liquid from the chamber 10, which constitutes a 65 continuation of said pump cylinder, is forced and thereafter ejected when the pump is operated.

The head is provided at one side with an extension 14 having a passage 15, cored or otherwise formed therein, which serves as an inlet passage to the chamber 10. The wall 75 of the extension 14 is provided with a port 16 which is adapted to afford communication between the inlet passage 15 and a valve chamber 17 formed in a valve housing 18 which is united with the head 9 and extension 14, the chamber 17 being at all times maintained in communication with the chamber 10 through a port 19 formed in the wall 80 of the head 9.

Within the chamber 17 is carried a valve 85 cage 22 which includes a central or hub portion 23 having a central longitudinal opening 24 formed therein. The hub portion 23 carries a pair of ribs 26 which are spaced from each other and project an appreciable 90 distance from one end of the hub portion 23, as shown most clearly in Figures 6 and 7. The hub portion 23 also carries a relatively short rib or lug 27 arranged intermediate the ribs 26 and spaced therefrom. The ribs 26 95 and 27 are adapted to fit into the spaces afforded between a plurality of inwardly projecting ribs 21, which are formed on the wall of the chamber 17, so that when the valve cage 22 is inserted into the chamber 17 100 it is locked or held against rotative displacement.

Within the chamber 17 and intermediate the ribs 26 and the inner wall of such chamber, there is confined an intake valve in the 105 form of a ball 28 which is adapted to cooperate with a valve seat 29 to close communication between the chamber 10 and intake pas-

sage 15 when liquid is being expelled from the chamber 10 through the nozzle tube, not shown.

When liquid is being expelled from the chamber 10 through said nozzle tube, it is desirable, as previously stated herein, to permit the escape of a small quantity of liquid from the chamber 10 back into the liquid supply, and to accomplish this, a relief valve 31 is provided. The relief valve 31 is carried within a pocket 32 formed in one end of the hub portion 23 of the valve cage 22 and adapted to seat upon the valve seat 33 formed at one end of the passage 24. A cover plate 34 carried within the chamber 17 at one end thereof serves to retain the valve cage 22 within the chamber 17 as shown in Figures 2, 3 and 4. The cover plate 34 is provided with a boss 35 which is formed with a vent 36 and projects into the pocket 32 so as to limit the movement of the valve 31 in its movement away from the seat 33. In order that the valve 31 may not obstruct the escape of liquid through the vent 36, the boss 35 is cut away as shown at 37 thus providing a substantial clearance between the valve 31 and the vent 36 as shown in Figures 2 and 3.

In operation, when liquid is being drawn into the chamber 10 from the intake passage 15 through the port 16, chamber 17 and port 19, the valve 28 is unseated from its seat 29, as shown in Figure 3, and the relief valve 31 is maintained seated upon its seat 33, as shown also in Figure 3. The valve 31 thus closes communication between the chamber 10 and the exterior of the head 9 through the opening 24, pocket 32 and vent 36, so that the only communication between the chamber 10 and the exterior of the head 9 is afforded through the intake passage 15, port 16, chamber 17 and port 19. On the other hand, when liquid is being expelled from the chamber 10 through the nozzle tube, not shown, communication between the chamber 10 and the intake passage 15 is closed by reason of the fact that the valve 28 is seated upon its seat 29 as shown in Figure 2. Under such conditions, however, the relief valve 31 is lifted from its seat 33, as shown also in Figure 2, whereby communication between the chamber 10 and the exterior of the head 9 is established through the passage 24, pocket 32 and vent 36 thus permitting a small quantity of liquid to escape back into the liquid supply, with the

result that the pump may be operated without apparent stiffness and without detracting from its efficiency.

What is claimed is:

1. A pump head having an intake passage, a relief vent and a valve chamber, the wall of said valve chamber being provided with an intake valve seat and a plurality of spaced ribs, a valve cage carried within said chamber and provided with an opening and a relief valve seat, said valve cage being formed with a plurality of ribs adapted to cooperate with the first mentioned ribs to anchor said valve cage against turning within said chamber, an intake valve carried within one end of said valve cage and adapted to cooperate with said intake valve seat to open and close said intake passage, and a relief valve located within the opposite end of said valve cage and adapted to cooperate with said relief valve seat to close and open said relief vent as said intake valve is moved to open and closed positions respectively. 60

2. A pump head having an intake passage, a relief vent and a valve chamber, the wall of said valve chamber being provided with an intake valve seat and a plurality of spaced ribs, a valve cage carried within said chamber and provided with an opening and a relief valve seat, said valve cage being formed with a plurality of ribs adapted to cooperate with the first mentioned ribs to anchor said valve cage against turning within said chamber, an intake valve carried within one end of said valve cage and adapted to cooperate with said intake valve seat to open and close said intake passage, a relief valve located within the opposite end of said valve cage and adapted to cooperate with said relief valve seat to close and open said relief vent as said intake valve is moved to open and closed positions respectively, a closure plate at one end of said chamber and serving to retain said valve cage against longitudinal displacement within said chamber, and a tubular boss carried by said closure plate and cooperating with said relief valve to limit its movement away from closed position, said boss being relieved whereby an unobstructed passage through said vent is maintained when said relief valve is in its open position. 90

In testimony whereof, I have affixed my signature to this specification.

PETER GRAHAM MACGREGOR.
